CLAIM

We claim the ornamental design for a Wi-Fi device, as shown and described.

DESCRIPTION

FIG. 1 is a front perspective view of a Wi-Fi device;
FIG. 2 is a rear perspective view of the Wi-Fi device;
FIG. 3 is a bottom perspective view of the Wi-Fi device;
FIG. 4 is a front view of the Wi-Fi device;
FIG. 5 is a rear view of the Wi-Fi device;
FIG. 6 is a left side view of the Wi-Fi device;
FIG. 7 is a right side view of the Wi-Fi device;
FIG. 8 is a top view of the Wi-Fi device; and,
FIG. 9 is a bottom view of the Wi-Fi device.

The broken lines depict portions of the Wi-Fi device that form no part of the claimed design. The shade lines shown

(Continued)

throughout the views are intended to indicate surface contour and are not intended to be surface ornamentation.

1 Claim, 9 Drawing Sheets
